UNITED STATES PATENT OFFICE.

MATTHEW C. ARMSTRONG AND RICHARD ARMSTRONG, OF HAMPTON, VIRGINIA.

MARKING BIVALVES.

1,195,946.

Specification of Letters Patent. Patented Aug. 22, 1916.

Application filed October 27, 1913. Serial No. 797,592.

To all whom it may concern:

Be it known that we, MATTHEW C. ARMSTRONG and RICHARD ARMSTRONG, citizens of the United States, residing at Hampton, in 5 the county of Elizabeth City and State of Virginia, have invented certain new and useful Improvements in Marking Bivalves, of which the following is a specification, reference being had therein to the accompanying drawing.

This invention relates to the marking of oysters, clams, and other bivalves in such manner that an identifying device, symbol, or mark placed thereon shall remain on the 15 part on which the edible portion of the bivalve is served and in such place that it may be seen readily by the person before whom the same is placed.

As is well known, it is a common practice 20 among some restaurateurs and others to serve on the "half-shell" to customers other than the particular brand or kind of oysters or other bivalves ordered, and the ordinary customer has no way of knowing that he is 25 getting what his order calls for.

This invention contemplates the attachment of an identifying device on the so-called under portion of the shell of a bivalve upon which the edible portion is served 30 in such manner that it will indicate to the purchaser its origin or kind.

The device is so placed that it will stay in 35 place during shipment before the shells are opened and in such position that it is visible both before and after a bivalve is opened and displayed on the "half-shell".

When read in connection with the description herein, the characteristics of the invention will be apparent from the accompanying 40 drawing, forming part hereof, wherein the invention is exemplified in association with an oyster, but it is to be understood that it is equally applicable to other bivalves.

Like reference characters refer to corresponding parts in the views of the drawing, of which—

Figure 1 is a plan view of an oyster prepared for application of an identification device thereto; Fig. 2 is a plan view of an oyster with an identification device applied thereto; Fig. 3 is a plan view of the oyster with its top shell removed; and Fig. 4 is a plan view of an identification device.

In carrying out the invention, a hole is bored through, or otherwise made in, the

under part of the shell, at a place that is outside of, or in that portion of its area that is not lapped by, the upper part of the shell. Preferably the hole is placed at a place beyond the ligament or hinge connecting the upper and lower parts of the shell, as shown at 5, care being taken not to pierce or otherwise interfere with the hinge or upper part of the shell, in order that the edible contents 65 of the shell may not be injured. The hole so formed affords means for attaching an identification device or mark to the shell.

The invention further comprises the use 70 of an identification device of the general characteristics of that shown by Fig. 4, which includes a head or enlarged portion 6, adapted to bear any suitable marks, words, or the like, and a shank 7 adapted to be disposed in the hole in the shell and operating 75 to hold the head in place.

Preferably the device is made of comparatively thin material, such as pliable sheet metal, whereby the free end of the shank, after being passed through the hole, may be 80 bent or turned to hold the device in place, but it is not the intention to be restricted necessarily to the use of exactly that form of device. Usually the head portion is of such size that it will extend beyond the end 85 of the shell and can be seen from all sides before the bivalve to which it is secured is opened.

It will be apparent that the device is 90 unmistakably visible when the under part of the shell is lying outside down as is the case after the bivalve is opened and the contents thereof are in that part of the shell and ready to be eaten, and that the marker is not 95 hidden from view as it would be if it were applied to the under surface of the major portion of the under part of the shell.

The hole having been formed in the shell, the marker or identification device is applied 100 to the shell by passing the shank into or through the hole, and thereafter deflecting or bending the free end of said shank substantially as seen in Figs. 2 and 3, whereby the marker is held securely in place.

By reason of our novel construction and 105 collocation of the identifying device with respect to the portion of the shell of the bivalve outside of or beyond the ligament or hinge thereof, which connects the upper and lower parts of the shell, it will be apparent 110 that the bivalve will be uninjured during or by the application of the identifying device

thereto. Furthermore, the identification device will be effectively retained in position during shipment and will not become readily disconnected during handling, and will be 5 readily visible to the opener both before and after the bivalve is opened, and when the bivalve is served on the "half shell", the latter together with its identifying device will appear substantially as shown in Fig. 10 3, so that the consumer can see that he has been served with exactly what he ordered.

We are the first in the art to apply to an oyster or other bivalve in the manner described, an identification device of any character 15 which will be visible to the opener during and after the bivalve is opened and which will be also visible to the consumer, when the oyster is served "on the half-shell", and our claims are therefore entitled to the 20 broad interpretation which is accorded to inventions of this character.

It will now be apparent that we have devised a novel and useful improvement in marking bivalves, which embodies the features 25 of advantage enumerated as desirable in the statement of the invention and the above description, and while we have, in the present instance, shown and described preferred embodiments thereof which will give 30 in practice satisfactory and reliable results,

it is to be understood that the same is susceptible of modification in various particulars without departing from the spirit or scope of the invention or sacrificing any of its advantages.

35

Having thus described our invention, what we claim as new, and desire to secure by Letters Patent, is—

1. Means for identifying oysters consisting of a tag attached to that part of the 40 shell on which the oyster is to be served at a point outside of the ligament or hinge of said oyster, whereby when the oyster is opened, said tag remains attached to the part to be served.

45

2. An improvement in the art of identifying oysters which consists in attaching a tag to that part of the shell on which the oyster is to be served at a point outside of the ligament or hinge of said oyster, whereby when the oyster is opened, said tag remains attached to the part to be served.

50

In testimony whereof, we have affixed our signatures in the presence of two witnesses.

MATTHEW C. ARMSTRONG.
RICHARD ARMSTRONG.
